(57) **CLAIM**

The ornamental design for an input for an electronic device, as shown and described.

DESCRIPTION

FIG. 1 is a bottom front perspective view of a component for an electronic device showing the claimed design;

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

The broken lines in the figures illustrate portions of the component for an electronic device that form no part of the claimed design.
